UNITED STATES PATENT OFFICE

FERDINAND MALLGRAF, OF LITTLE NECK, NEW YORK, ASSIGNOR TO THE AMERICAN TOBACCO COMPANY, OF NEW YORK, N. Y., A CORPORATION OF NEW JERSEY

DISPLAY DEVICE

Application filed June 10, 1932. Serial No. 616,548.

My present invention relates to display devices such as portable signs used to display dummy cartons representing standard cartons of merchandise, and particularly to 5 means for securely attaching the dummies to the sign.

Prior to my invention, it has been the general custom in advertising cigarettes and other goods sold in standard packages, to 10 provide a sign portraying matter or pictorial representations calculated to attract attention and to arrange on the sign, in an orderly and attractive manner, dummy cartons simulating the standard cartons of the 15 goods advertised. Such signs are frequently placed in store windows as part of a general window display, and in most cases the signs and dummies are subjected to atmospheric conditions, and particularly to the rays of 20 the sun coming through the window. Usually the dummies are simply pasted on the sign in face to face relation, that is, one surface of the dummy carton is placed against an area of the sign with a layer of adhesive 25 uniting the two surfaces. It has been found that the glue or paste used in this securing the dummies on the sign loses its adherent qualities and some of the dummies fall off of the sign, thus detracting from the appearance of the display and sign.

The principal object of the present invention is to so construct the dummy and the sign, particularly at the areas of each which are brought into contact when the dummies 35 are placed on the sign, so that the dummies will be very tightly secured to the sign and the adhesive will be protected from the sun to prolong its adherent qualities. The invention furthermore provides a construction 40 and arrangement of dummy and sign such that even if the adhesive does lose its adherent qualities the dummy will still be retained on the sign instead of dropping off.

The foregoing and other objects and advantages of the invention will become ap-

parent and will be particularly pointed out during the course of the following detailed description of the accompanying drawing, wherein are shown preferred embodiments of the invention, and in which

Fig. 1 is a front elevation of a sign embodying the invention and showing several dummies applied thereto;

Fig. 2 is a sectional view on the line 2—2 of Fig. 1;

Fig. 3 is a sectional view on the line 3—3 of Fig. 1;

Fig. 4 is a perspective view of a dummy embodying the invention and illustrating one embodiment of the retaining means on 60 the dummy;

Fig. 5 is a view similar to Fig. 4 showing a modification of the invention; and

Fig. 6 is a view similar to Fig. 4 showing another modification as applied to the structure of Fig. 4.

Referring to Figs. 1—4, the numeral 7 designates the top or display portion of a sign arranged above supporting standards 8. A supporting strip 9 is hingedly secured to the back of the sign to hold the same in upright position. Arranged around the portion 7 of the sign are a plurality of openings 10, each being shown as of polygonal formation and having converging sides of slightly greater length than the ends. The openings may be arranged or grouped in any relative positions, and the circular arrangement shown is merely for the purpose of illustration, as it conforms with the configuration of the portion 7. The area of the openings 10 is also less than the area of the dummies 11 which are secured on the sign one over each opening in the manner clearly shown in Figs. 2—4, wherein each of the dummies has provided on its back a pair of flaps 12. The flaps 12 are provided by cutting the back of the dummy along the lines 13 and 14, the lines 13 conforming substantially to the sides of the openings 10 in length and relative ar-

angement and the line 14 dividing the flaps. A hole 15 may be provided between the flaps 12 so that the finger or an implement may be inserted therein between the flaps to readily 5 separate them and permit bending outwardly and backwardly along the transverse creases 16 at the ends of the flaps. Creases 17 are also provided across the flaps at a distance from the creases 16 corresponding substantially 10 to the thickness of the material from which the sign is made.

To apply the dummies to the sign, the flaps 12 are preferably first pulled slightly outward from the dummy so that they can 15 pass through the openings 10 when the dummy is brought into face to face relation with the sign 7 and in proper registry with the openings 10, after which an adhesive is applied either to the back of the sign above 20 and below the openings 10, or to the rear face of the flaps 12, or both, and the flaps are bent sharply on their creases 16 and 17 until the rear face of the flaps are brought against the rear of the sign 7 as clearly shown in Fig. 3 25 with the adhesive 18, such as glue or paste therebetween.

I have found that dummies constructed as above described and secured to the sign in the manner specified, will remain in place on 30 the sign under all conditions. Even if the adhesive 18 loses its adherent qualities, which is not as likely as with the adhesive applied on the front of the sign, the flaps 12 having been bent sharply around the sign at the top 35 and bottom of the openings 10 will serve to retain the dummies on the sign.

Referring to Fig. 6, it will be noted that the faces of the flaps 12 which confront the back of the sign 7 are provided with indentations 19 to provide a surface with little 40 pockets or openings into which the adhesive may flow, so that the flaps will be more firmly united to the sign by the adhesive. This feature or forming indentations on a surface 45 to be united to another surface is not limited to the use on flaps secured to the sign in the manner above described. In fact, this feature may be utilized in connection with various surfaces united in face to face relation with 50 other surfaces.

In Fig. 5, I have shown a modification wherein a single flap 20 formed by cutting the back of the dummy from the crease 21 longitudinally and substantially parallel to the 55 sides of the dummy, and then transversely across the back of the dummy. The flap may be provided with rounded corners if desired, although the shape of the flap is not essential to the invention, the important point being 60 to provide the crease 21 and crease 22 spaced therefrom a distance substantially equal to the thickness of the sign, whereby the flap may be inserted through an opening in the sign and then bent down against the back 65 of the sign with the portions between the

creases 21 and 22 against an edge of an opening in the sign. The flaps 20 may be provided with indentations such as shown and described in connection with Fig. 6 or it may have a perfectly plain surface, and in either event will be united to the back of the sign by an adhesive, as shown in Fig. 3 in connection with the flap 12.

I wish it to be understood that I do not limit the invention to the particular shape of the flaps nor to any particular number or any particular arrangement of flaps, as I deem it within the invention to provide the flaps to open in any direction and to be made in any shape, number, and size.

I claim:

1. A display device of the class described, including a sign providing a support, a dummy package formed independent of the sign, the sign having an opening over which the dummy is mounted at the front of the sign, and a flap on the dummy extending through said opening and provided with creases at the front and back edges of the opening, the end of said flap being bent over the back of the sign, said dummy being of greater dimension than said opening whereby marginal portions around said flat abut the face of the sign.

2. A display device of the class described, including a sign providing a support, a dummy package formed independent of the sign, the sign having an opening over which the dummy is mounted on the front of the sign, and flaps on the dummy of substantially the same size and shape as the opening, said flaps being inserted through said opening and bent toward the back of the sign to hold the dummy on the front of the sign, said dummy being of greater dimension than the opening whereby marginal portions around the flaps abut the face of the sign.

3. A dummy package for advertising comprising a box having its back cut along lines adjacent and between opposite sides and transversely between said lines to provide a pair of flaps terminating adjacent and between the ends of the back and bendable outwardly from the back of the dummy to connect the same to a support.

4. A dummy package for advertising comprising a box having its back cut along lines adjacent opposite edges and transversely between said lines to provide a pair of flaps terminating adjacent the ends of the back and bendable outwardly from the dummy to connect the same to a support, and an opening along said transverse cut between the flaps to receive an implement to facilitate bending said flaps outwardly.

5. In combination with a display sign, a dummy carton, the sign having an opening over which the dummy is disposed, the dummy being of greater width than the opening and having flaps on its side which covers

the opening to fold over the edges of the opening and against the back of the sign.

6. In combination with a display sign, a dummy carton, the sign having an opening over which the dummy is disposed, the dummy being longer than the opening and having flaps on its side which covers the opening to fold over the edges of the opening and against the back of the sign, and 10 said flaps being of substantially the same size and shape as the opening.

Signed at New York in the county of New York and State of New York this 7th day of June A. D. 1932.
